6 - FIG.

FIGURE 1

FIGURE 1 is a front, top and left end perspective view of a magnetic tape transport, showing my new design;

FIGURE 2 is a top plan view;

FIGURE 3 is a fragmentary front elevational view, the bottom being broken away for convenience in illustration;

FIGURE 4 is a rear, top and right end perspective view;

FIGURE 5 is a rear elevational view;

FIGURE 6 is a right end elevational view, to an enlarged scale; and

FIGURE 7 is a left end elevational view thereof, to an enlarged scale.

The grillework is continuous within the areas as shown.

The broken line showings of magnetic tape and tape reels in FIGURES 1, 2, 4 and 5 are for illustrative purposes only.

I claim:

The ornamental design for a magnetic tape transport, substantially as shown and described.
